Attorney.

UNITED STATES PATENT OFFICE.

CHARLES HENRY PARKEE, OF CODSALL, ENGLAND.

APPARATUS FOR THE DISTILLATION OF COAL AND SIMILAR CARBONACEOUS SUBSTANCES.

Application filed January 27, 1928, Serial No. 248,965, and in Great Britain September 25, 1926.

This invention relates to apparatus for the distillation of coal and similar carbonaceous substances, and especially to apparatus for carrying out a method of distillation in which the distillation is effected in two stages, the distillation proceeding in the first stage as the result of heat being applied to the retort or by internal application of heat through the medium of heated gas, and the second stage proceeding in a storage chamber under the heat acquired in the first stage without the necessary external application of heat to the retort or chamber within which the second stage is effected and without additional heat necessarily being applied through the medium of heated gas.

The invention further is especially applicable in the distillation of coal at low and medium temperatures and for the production of a smokeless fuel having a high or moderately high volatile content, while the invention is especially advantageous in apparatus in which the retort or the like in which the first stage of distillation is effected is separated by means of a door from the retort or chamber or the like in which the second stage of distillation is effected.

According to the invention, in addition to the means provided at the upper end of the upper retort whereby the gas evolved may be withdrawn, means are also provided whereby gas evolved may be withdrawn from the vicinity of the junction between the upper retort or the like and the lower chamber or the like. The gas thus withdrawn by the means adjacent the lower part of the retort is conducted upwards by an outlet pipe and delivered to the main ascension pipe leading from the upper part of the retort at a point behind the anti-dip valve by which the retort is protected and isolated during the discharge. It will be understood that the tar which condenses in the auxiliary pipe is allowed to fall into an additional tar main in which the end of the ascension pipe is sealed. The tar is advantageously allowed to pass away from the additional tar main over a dam which thus ensures the maintenance of a constant level in the main.

The invention is illustrated by way of example in the accompanying diagrammatic drawing, which represents a sectional elevation of a retort and retort setting.

The retort *a*, in which the first stage of the process of distillation referred to is effected, is provided at the upper end with a charging

hood *b* to which is connected a gas outlet conduit pipe *c* for delivering the gas into the hydraulic main *d* by way of the anti-dip valve *e*. Below the retort *a* there is disposed the casing or chamber *f* in which the second stage of the process of distillation is effected and at the upper end of this retort in the vicinity of the door *g* closing the retort *a*, gas is withdrawn, according to the invention, by a pipe or conduit *h* connected with an ascension pipe *i* serving to convey the gas upwards and to deliver the gas to the ascension pipe *i* at a point to the rear of the anti-dip valve *e*. The connection of the ascension pipe *i* with the outlet pipe *c* may be provided with a valve so that communication between the said pipes may be broken when desirable. The ascension pipe *i* extends downwardly into an additional tar main *j* in which the end of the pipe is sealed by the tar which is maintained at a determined level by means of a dam over which it is permitted to discharge from the tar main *j*, which may be provided with a suitable cover plate.

The hydraulic main *d* may have one or both side walls inclined outwardly, or it may be provided with laterally disposed chambers or pockets having cover plates, to facilitate the use of appliances for clearing the inner surface of the main.

A discharging aperture *f* is provided adapted to be closed by a cover plate in position immediately opposite to the inclined bottom *f* of the receptacle.

It will be understood that the invention is not limited to the details of construction hereinbefore described. Thus, in the construction illustrated there may also be provided a conduit for the withdrawal of gas from the lower part of the retort *a* in the vicinity of the door *g* and connected to the pipe or conduit *h* or to the ascension pipe *i* or such a conduit may be provided alternatively to the pipe or conduit *h*.

No broad claim is made to the provision of means for withdrawing gas from a point adjacent to the discharge door of a retort and for introducing it into the main gas delivery pipe leading from the upper part of the retort behind the valve controlling communication with the hydraulic main.

I claim:

Apparatus for the distillation of coal and other carbonaceous substances comprising a vertical retort and a casing having a sec-

ondary storage chamber therein below said retort, said storage chamber havin' substantially the same capacity as said retort and hav-
ing a sloping bottom and a side discharge out-
5 let, a door at the bottom of the retort by which the charge from the retort may be allowed to fall into the secondary storage chamber, a gas outlet pipe communicating with the upper end of the retort and a tar main into which
10 the said outlet pipe extends; a second gas out-

let pipe communicating with the upper end of said secondary storage chamber adjacent said door, an ascension pipe with which the last mentioned outlet pipe is connected, the said ascension pipe communicating at its upper end with the outlet pipe from the upper end of the retort, and a second hydraulic main into which the lower end of said ascension pipe extends. 15

CHARLES HENRY PARKER.
